STAND FOR HOUSEHOLD PAPER ROLLS

Arne Nils Christian Sonnergaard, Lidingo, Sweden, assignor to AB Automatic, Stockholm, Sweden

Filed Apr. 13, 1972, Ser. No. 243,922

Claims priority, application Canada Feb. 24, 1972

Term of patent 14 years

Int. Cl. D6—99

U.S. Cl. D6—97

FIG. 1

FIG. 3

FIG. 2

FIG. 1 is a perspective view of a stand for household paper rolls in upright position and showing my new design;

FIG. 2 is a top plan view thereof; and

FIG. 3 is a fragmentary perspective view showing the lower portion of the stand in greater detail.

I claim:

The ornamental design for a stand for household paper rolls, as shown.
